FUSIBLE ELEMENT FOR INCLOSED ELECTRICAL FUSES.

1,227,752.

Specification of Letters Patent.

Patented May 29, 1917.

Application filed October 27, 1916. Serial No. 127,990.

To all whom it may concern:

Be it known that I, ROBERT C. COLE, a citizen of the United States, residing at Hartford, in the county of Hartford and State of Connecticut, have invented a new and useful Improvement in Fusible Elements for Inclosed Electrical Fuses, of which the following is a specification.

This invention relates to the construction 10 of the fusible element of inclosed electrical fuses which have multiple links.

It is required of fusible links that they carry a rated amount of current and a certain percentage of overload continuously, 15 and that they melt or blow within a predetermined time after the maximum amount of overload has been reached. To accomplish this links in the form of flat strips have been calibrated by cutting away portions 20 of the edges or perforating the strips at the middle, and numerous expedients have been suggested to likewise calibrate round wire fusible links. It is well known, however, that fusible links of circular cross 25 section are inclined to hang, that is, are sluggish and tend to remain in a molten condition when a gradually increasing overload reaches its maximum so that the fuse does not open and protect the circuit when it is 30 desired it should.

The object of the present invention is to in a very simple way accomplish the calibration of multiple strip fusible elements in which the links are made of round wire or 35 are circular in cross section. This object is attained by bending the fusible links so that they approach and touch or almost touch each other at the middle of the fuse, thereby increasing the heating effect at the middle 40 by reducing the heat conducting capacity of the filling by which they are surrounded at that point. This concentration of heat in this manner at the middle reduces the overload carrying time without affecting 45 the normal carrying capacity, and causes the links to melt or blow at the center at the time desired.

Figure 1 of the accompanying drawings shows a longitudinal section of an inclosed 50 fuse having a fusible element consisting of a plural number of round wires formed according to this invention. Fig. 2 shows a transverse section on the plane indicated by the dotted line 2-2 on Fig. 1. Fig. 3 shows 55 a transverse section on the plane indicated

by the dotted line 3-3 on Fig. 1. Fig. 4 shows a side view of a fusible element of modified form.

The insulating tubular casing 1 with the metallic end caps 2 and exterior knife-blade 60 terminals 3 are of common form and construction and, of course, these may be varied in size, shape and style.

The fusible element has terminals 4 which extend through the end caps and are fastened to the knife-blade exterior terminals. On the inner ends of the fusible element terminals are frames or disks 5 of conducting material, and secured to these disks or frames are the ends of the fusible links 6. 70 These links, of which there may be any desired number depending upon the rated carrying capacity of the fuse, are of compact cross section, desirably circular, and although spaced apart at each end, they are 75 brought together so as to touch or almost touch at the middle of the casing. The links may be brought together by bending them inward sharply, as shown in Fig. 1, or they may be brought together gradually, as 80 shown in Fig. 4. The fusible element thus formed is placed in the casing which is then filled with granular heat insulating and electrical non-conducting material of approved condensing composition 7.

As a result of this construction each link tends to heat the others at the middle when a maximum current is flowing, owing to the proximity of the links at the middle, to the reduction of the effective filling material between the links at the middle, and to the increased amount of filling material outside of the links at the middle so that there is less radiation at the middle than at the ends to the tube and outer atmosphere. These factors combine to concentrate the heating effect at the middle of the fuse and, while under normal conditions the carrying capacity is not affected, under overload conditions the carrying time is reduced so that 100 the element will melt more quickly at the middle of its length than with the ordinary straight round wire links which are sluggish and uncertain. This construction makes it possible to calibrate a fuse so as to obtain 105 a short predetermined blowing time on hot or cold overload.

The invention claimed is;

1. A fusible element for an inclosed fuse consisting of a plural number of fusible 110

links of compact cross section spaced apart at their ends and brought into proximity with each other at the middle of their length.

- 5 2. A fusible element for an inclosed fuse consisting of a plural number of fusible links of round cross section spaced apart at their ends and brought together intermediate the ends.
- 10 3. A fusible element for an inclosed fuse consisting of a plural number of fusible links of compact cross section held in proximity with each other at the middle and spaced apart at the ends, conducting frames

holding the ends of the links apart, and 15 terminals extending from the conducting frames.

4. A fusible element for an inclosed fuse consisting of a plural number of round fusible wires, said wires being closer together at the middle than at their ends, 20 disks holding the ends of the wires apart, and terminals extending from the disks.

5. A fusible element for an inclosed fuse consisting of a plural number of round 25 fusible wires brought together at the middle and held spaced apart at the ends.

ROBERT C. COLE.
